(57) **CLAIM**

The ornamental design for a wheel with five spokes, as shown and described.

DESCRIPTION

FIG. 1 is a front perspective view of a wheel with five spokes according to my invention. The rear side of the wheel is identical to the front side. The outer ends of all spokes are identical; and,

FIG. 2 is a cross-sectional view taken as indicated by the line 2—2 of FIG. 1.

The invention is a vehicle wheel that is has five spokes that each flare out from the hub of the wheel and are split into two arms at their rim ends and have a sculpted, flaring appearance.
